UNITED STATES PATENT OFFICE.

EDWARD WILLIAM GRIFFIN KUGLEY, OF CHARLESTON, SOUTH CAROLINA.

FREIGHT-CAR DOOR.

Application filed June 19, 1923. Serial No. 646,389.

This invention relates to sliding doors for freight cars, and is more particularly directed to an automatic latching means for car doors.

5 An object of the invention is the provision of a device for automatically securing a freight car door in either an open or closed position which is equally adaptable for use on both a single and double door.

10 The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the 20 salient features of the invention as expressed in the appended claim.

In the drawing:—

Fig. 1 is a side elevation of a freight car with my invention applied to the sliding 25 car doors.

Fig. 2 is a vertical transverse section of the same.

Fig. 3 is a transverse section of the track which slidably supports the car doors.

30 Fig. 4 is a view in perspective of the automatic latching means.

Fig. 5 discloses detail views of the brackets in which the operating rod for the latches is mounted.

35 Fig. 6 discloses detail views of the sockets for receiving the latching means.

Fig. 7 shows a front and end elevation of the hangers for slidably mounting the doors on the car.

40 Referring to the drawings, 1 designates a freight car with a side opening closable by sliding doors 2 and 3, or a single door may be employed for the purpose when desired. Directly above the opening and on the outer wall 4 of the side of the car is secured a water guard 5 which extends lengthwise of the car. As shown in Fig. 3, the water-guard is of angle iron construction with the vertical flange secured to the wall of the car, 45 while the other flange extends horizontally at right angles to the vertical flange for supporting the track 6. Spacer blocks 7 are likewise supported by the horizontal flange and positioned between the track 6 and the vertical flange of the water guard. The track 6 and spacer blocks 7 are secured

by means of bolts or screws to the side wall of the car.

The doors are suspended from the tracks by means of cast iron hangers 8 secured adjacent the upper ends of the doors with rollers 9 rotatably mounted between the front plate of the cast iron hanger 8 and a rear return portion 10 spaced from the front plate of the hanger 8. The rollers 9 are mounted on pins 11 secured in the U-shaped portion of the hanger. In order that the doors may ride easily on the tracks 6, I have provided two grooved rollers in each hanger 8.

70 The lower end of the doors is held in position and prevented from movement laterally from the side of the car by a guard rail 12 which is likewise of angle iron construction and secured to the outer wall 4 of the car.

75 Posts or door jambs 13 and 14 are mounted vertically in the side wall 4 of the car and spaced from each other a distance to be spanned by the width of either door 2 or 3.

80 A rod 15 is rotatably mounted on the outer side wall of the door 2 by means of a pair of brackets 16 secured on said door and adjacent the medial line of said door. A pair 85 of spaced brackets 17 and 18 are secured to the door 2 adjacent the side edges.

85 On the opposite ends of the rotatable rod 15 are secured inwardly-projecting latch members 19 and 20 having upstanding lugs 21 for a purpose which will be described later. Secured centrally of the rod 15 and depending downwardly therefrom is a hasp 22 with a slot 23 in its lower end adapted to receive a U-shaped or perforated keeper 24. The U-shaped member 25 is adapted to be inserted through the keeper 24 for maintaining the hasp 22 in position. A chain 26 secured at one end to the car door 2, and at its other end to the U-shaped member 25 is adapted to prevent loss of said U-shaped member.

100 The latch members 19 and 20 may be welded or pinned to the ends of the rotatable rod 15, while the hasp 22 is welded to the central portion of said rod and adapted to be oscillated between the brackets 16. The brackets 17 and 18 are provided with laterally-extending lugs 27 which project beyond the side edges of the car door 2 and over the keepers 28 and 29, which are provided with pockets adapted to receive the

latch members 19, the lugs 27 limiting movement of the latch members 19 and 20. The keepers 29 are provided with an upper and lower pocket 30 and 31, respectively.

5 As shown in Fig. 6, a face plate 32 extending outwardly from the side edges of the pockets 30 and 31 is adapted to be secured to the posts 13 and 14 when the pockets 30 and 31 are seated within recesses formed 10 within said posts. A lip 33 formed by an extension of the plate 32 projects downwardly across the opening in the pockets 30 and 31 and provides a keeper adapted to engage the lugs 21 of the latch members 19 and 20 15 for preventing outward movement of the doors when the lugs are so engaged with the respective keepers, whether the doors are in open or closed position.

As shown in Fig. 1, the keeper 28 on the 20 left hand end of the door 2, which is engaged by the latch member 19, is located at a higher elevation than the keeper 28 engaged by the latch member 20 on the door 3.

The rotatable rod 15, with its latch members 19 and 20 and the hasp 22 of the door 2, is similarly applied to the door 3 with the exception that the rotatable rod 15 is located at a lower plane than the rod 15 of the door 2 so that the latch member 19 of the door 3 30 will engage in the lower pockets 31 of the keepers 29 instead of the upper pockets, as do the latch members 20. The keeper 28, which is located to the right hand side of door 3 and engageable by the latch member 20, is likewise located at a lower plane than the keeper 28 on the left hand end of door 2.

In the operation of my automatic latching means, the U-shaped member 25 is removed from the keeper 24 when the hasp 22 40 may be elevated, thereby rotating the rod 15 and causing the latch members 19 and 20 to be oscillated sufficiently until they engage the lugs 27 on the brackets 17 and 18, whereby further movement of the latch members 45 will be prevented. In this position of the latch members, the door is free to be moved longitudinally of the car and carried by the hangers 8 on the track 6.

When the door 2 is moved sufficiently to 50 the right to close the opening, shown in Fig. 1, after the latch members 19 and 20 have been released from their respective keepers, latch member 20 will automatically fall into the pocket 30 at the left hand edge of the door 3, while the keeper 19 will fall into pocket 30 now located at the left hand edge 55 of door 2 in its present position. The latches are urged to locking position by the weight of the released hasp 22. The lugs 21

of the latches engaged by the lips 33 projecting over the mouths of the pockets 30, 60 not only lock the door from sliding movement but likewise prevent the bottom of the door from being moved laterally from the side of the car.

65 The door 3 may be similarly moved to the left after the hasp 23 has been elevated to release the latch members 19 and 20 from their respective keepers. The door 2 must be returned to its normal position before 70 door 3 may be set in motion. When the door 3 has been moved sufficiently to the left, the latch members 19 and 20 will automatically engage their respective keepers 31 upon release of the hasp 22 whereby door 3 will be 75 locked against further movement.

80 It is seen from the relative predetermined positions of the cooperating keepers 28 and 29 upon opposite sides of each door and especially of the spacing of the keepers 29 adjacent the inner sides of said doors that the doors may be locked with facility in either a closed or open position.

85 Furthermore, the spacing of the latches 19 and 20 equaling the spacing of the keepers 29 upon opposite sides of the opening in the side wall 4 of the car is a dominant factor 90 in establishing the locked positions, whether closed or open, of the sliding car doors.

95 What is claimed is:—

In a device of the character described, co-operative doors slidable on tracks, spaced brackets secured to each door, a rod rotatably mounted in the brackets on each door, a rod on one door being located above the rod on the other door, latches secured to the opposite ends of each rod and adapted to normally project inwardly from opposite side edges of a door, a hasp rigidly connected to each rod for rotating the same and for 100 maintaining the latches in the normal inward position, a keeper on the doors adapted to be engaged by the hasps for locking the hasps against movement to prevent rotation of the rods and releasing the doors, keepers 105 mounted in a fixed position relative to the doors and in the path of the latches located in different horizontal planes for receiving said latches when the doors are either in an open or a closed position, the keepers for 110 engaging the latches being provided with means at different horizontal levels to engage the latches located at different levels on the doors, lugs on the brackets projecting laterally from the sides of the door for limiting the latches to a ready latching position with their respective keepers.

EDWARD WILLIAM GRIFFIN KUGLEY.
